UNITED STATES PATENT OFFICE.

FRIEDRICH BECKER, OF OBERSTEIN, GERMANY, ASSIGNOR TO ISIDOR LIEFMANN, OF SAME PLACE.

BORING-MACHINE.

SPECIFICATION forming part of Letters Patent No. 240,643, dated April 26, 1881.

Application filed March 22, 1881. (No model.)

To all whom it may concern:

Be it known that I, FRIEDRICH BECKER, of Oberstein, Germany, have invented a new and useful Improvement in Boring-Machines, of 5 which the following is a specification.

The invention relates particularly to small machines employed for boring or drilling agates or jewels; but it may be embodied in machines for other purposes.

10 The invention consists, essentially, in a machine comprising a vertical spindle carrying a boring-tool, and adapted to be rotated in fixed bearings by a belt from a driving-shaft which carries a cam or wheel, a vertically-moving carriage which carries a vise or clamp, in which the stone or article to be bored is clamped, and a pivoted weighted lever having an adjustable screw-connection with said carriage, and serving to raise the carriage to press the stone or 15 other article carried in the vise or clamp against the boring-tool until a roller carried by the lever comes in contact with the said wheel or cam upon the driving-shaft, when further boring is prevented until the connection between 20 the weighted lever and the vertically-movable carriage is adjusted. The machine may thus be set to bore to a certain depth or size only and then stop boring, thus enabling one workman to attend to a number of machines.

25 In the accompanying drawings, Figure 1 represents a side view, partly in section, of a machine embodying my invention. Fig. 2 represents a front view thereof, and Fig. 3 represents a plan thereof with the spindle and its bearings removed to show the vise or clamp.

Similar letters of reference designate corresponding parts in all the figures.

30 A designates a portion of the bed of the machine, and B designates a frame supported upon a standard, B', erected upon the bed, and containing fixed bearings, in which a vertical spindle, a, may be rotated. Motion is imparted to the spindle a by a belt, b, from a driving-pulley, C, upon a driving-shaft, D, and said 35 spindle carries the boring-tool a'. The required tension may be applied to the belt b by an idler-pulley, e, arranged as clearly seen in Fig. 1.

Immediately below the spindle a are guides 40 or ways d, which may be adjusted accurately

toward or from each other by adjusting-screws e, and in the ways or guides d is arranged a carriage, f, which is free to move vertically, and carries at its upper end a vise or clamp, g, in which the agate or other article to be bored 55 is to be securely clamped. By the upward movement of the carriage f the article to be or being bored is fed toward the boring-tool a'.

E designates a lever, pivoted at h to a hanger, E², attached to the under side of the bed A, and at the end distant from the carriage f the lever is weighted by a weight, i. At the other end of the lever E is a rod or connection, j, which is connected with a screw, k, adapted to be turned in a nut in the bottom of the carriage f, and by turning the screw the carriage f may be raised or lowered relatively to the end of the lever E. At the weighted end the lever E has an upwardly-projecting arm, E', the upper end of which carries a roller, l, which 60 may engage with a wheel or cam, F, upon the driving-shaft D. The roller l might be dispensed with, and is considered as a part of the lever E E'.

In the operation of my machine it is obvious 75 that the weight i will tend to press the article to be bored up against the boring-tool a', and this will continue until the roller l is moved back against the wheel or cam F, which forms a stop to limit the upward movement of the 80 carriage f. Where the cam F is used, as soon as the roller l touches said cam a quick upward and downward movement will be imparted to the carriage f, which provides for introducing oil into the hole made by the boring-tool a' and prevents the tool from sticking. By turning the screw k to move it downward 85 in its nut the carriage will be raised relatively to the end of the lever E, with which it is connected, and the said lever will again raise the 90 carriage and press the work being done up against the boring-tool.

It will be understood that the screw k provides for setting or adjusting the machine to bore a hole of a certain size or depth, and 95 hence one workman may attend to a number of machines, which may all be driven from a single shaft, D.

A spring might be substituted for the weight i; but in either case the lever E may be re- 100

garded as weighted to exert an upward pressure on the carriage.

What I claim as my invention, and desire to secure by Letters Patent, is—

5 1. The combination, in a boring-machine, with the spindle rotating in fixed bearings, the driving-shaft, and the vertically-movable carriage, of a weighted lever, to which said carriage is connected, and through which it is raised, and a wheel or cam upon the driving-shaft, with which said lever comes in contact to limit the upward movement of said carriage, substantially as specified.

10 2. The combination, in a boring-machine, with the rotary spindle, the driving-shaft, and the vertically-movable carriage, of a weighted

lever having at one end an adjustable connection with said carriage, and a cam or wheel upon the driving-shaft, with which said lever comes in contact to limit the upward movement of the carriage, substantially as specified. 20

3. The combination of the carriage *f*, the rod or connection *j*, the screw *k*, the lever *E E'*, the roller *l*, the cam or wheel *F*, and the driving-shaft *D*, all substantially as specified. 25

In testimony whereof I have signed my name to this specification in the presence of two subscribing witnesses.

FRIEDRICH BECKER.
